United States Patent Office

Des. 179,336
Patented Dec. 4, 1956

179,336

GIRDLE

Anna Y. Bayer, North Haven, Conn., assignor to The Strouse Adler Company, New Haven, Conn., a corporation of Connecticut

Application August 6, 1956, Serial No. 42,528

Term of patent 14 years

(Cl. D20—2)

Fig. 1 is a front view of a girdle showing my new design; and

Fig. 2 is a rear view thereof.

I claim:

The ornamental design for a girdle, as shown.
